Primary Examiner — Raphael Barkai(74) *Attorney, Agent, or Firm* — Robert C Montgomery;
 Montgomery Patent & Design LP(57) **CLAIM**

The ornamental design for a video monitor, as shown and described.

DESCRIPTION

FIG. 1 is a perspective top side view of the video monitor, showing my new design;

FIG. 2 is a front side elevation view thereof;

FIG. 3 is a back side elevation view thereof;

FIG. 4 is a right side elevation view thereof;

FIG. 5 is a left side elevation view thereof;

FIG. 6 is a top side plan view thereof; and,

FIG. 7 is a bottom side plan view.

The dashed lines are intended to show boundary areas and form no part of the claimed design.
